UNITED STATES PATENT OFFICE.

ALEXANDRE LEFORESTIER, OF PHILADELPHIA, PENNSYLVANIA.

DESIGN FOR A HORN.

SPECIFICATION forming part of Design No. 30,473, dated April 4, 1899.

Application filed December 19, 1898. Serial No. 699,766. Term of patent 7 years.

To all whom it may concern:

Be it known that I, ALEXANDRE LEFORESTIER, a citizen of the United States of America, and a resident of Philadelphia, in the county 5 of Philadelphia, State of Pennsylvania, have invented a certain new and useful Design for a Horn, of which the following is a specification.

My invention relates to a new and original 10 design for a sound-amplifying horn to be attached to the diaphragm-case of a sound-reproducing machine.

It consists of a horn of substantially the 15 contour shown in the drawing.

The leading and essential feature of the 20 design consists of a horn having the shape shown.

As may be seen by reference to the drawing, the extreme end of small diameter of the 25 horn is bent at an angle to that part of the horn of which it forms an extension. From this bend the horn extends in a substantially straight direction for some distance and is

then curved downwardly, rearwardly and upwardly, and forwardly, the bend being in 25 the form of one section of a spiral. It then extends forwardly in a direction approximately parallel to and somewhat to one side of the straight part of the horn, above described, terminating at its outer end in a bell-shaped flare. 30

Along that part of the horn constituting the forward straight section thereof and at about the line of the center of gravity of the horn is attached means by which the horn 35 may be suspended.

What I claim is—

The design for a horn substantially as shown and described.

Signed by me, at Philadelphia, Pennsylvania, this 13th day of December, 1898. 40

ALEXANDRE LEFORESTIER.
